Filed May 8, 1972, Ser. No. 251,581

Term of patent 14 years

Int. Cl. D26—05

U.S. Cl. D48—23 A

FIG. 1 is an elevation of the light fixture showing my new design, the opposite side is similar;

FIG. 2 is a top plan view thereof;

FIG. 3 is a bottom plan view thereof;

FIG. 4 is an end view thereof, the opposite end being similar; and

FIG. 5 is a perspective view thereof on a reduced scale.

The chains are fragmentarily shown in FIG. 1 and omitted in FIG. 4 for convenience of illustration.

I claim:

The ornamental design for a light fixture, as shown and described.
